UNITED STATES PATENT OFFICE

WILLIAM V. POLICK, OF TACOMA, WASHINGTON.

RAILROAD-TIE.

1,110,229.

Specification of Letters Patent.

Patented Sept. 8, 1914.

Application filed May 1, 1914. Serial No. 835,715.

To all whom it may concern:

Be it known that I, WILLIAM V. POLICK, a citizen of the United States, residing at Tacoma, in the county of Pierce and State of Washington, have invented certain new and useful Improvements in Railroad-Ties, of which the following is a specification.

This invention relates to new and useful improvements in railroad ties, and has for 10 its principal object the provision of a tie which will prevent the rail from spreading, sinking or creeping.

Another object of the invention is the provision of a tie which retains the resilient 15 quality of the old type of wood tie along with the advantages which are present in the use of a metallic tie.

A further object of the invention is the provision of a simple and effective means 20 for securing the rails in place on the tie and preventing the same from becoming displaced.

A still further object of the invention is to provide a tie which may be formed of a 25 single sheet of metal without materially increasing the expense of manufacture.

Still another object of the invention is to provide a tie which is arranged so that an extension may be secured thereto in order 30 that the tie may be used at switches and similar places where it is desirable that a tie of greater length be provided.

With the above and other objects in view, the invention consists in the novel combination 35 and arrangement of parts which will be fully set forth in the following specification and accompanying drawings, in which,

Figure 1 is a side view elevation of a railroad tie constructed in accordance with this 40 invention, Fig. 2 is a top plan view of the same, Fig. 3 is a detail end elevation of the tie, Fig. 4 is a longitudinal sectional view of a fragment of a tie constructed in accordance with this invention showing the rails 45 in place and the method of securing the same, and, Fig. 5 is a detail view showing the method of connecting a plurality of sections together to lengthen the tie.

Referring now to the drawings by characters of reference, the numeral 1 designates 50 as an entirety a tie constructed in accordance with this invention which comprises the single strip of metal 2 having formed centrally thereof a plurality of spaced slots, 55 the longitudinal edges of which are bent downwardly as clearly illustrated in Fig.

4 and serrated to form the notches 3, the use of which will appear hereinafter. The lateral edges of the body portion 2 are provided with the depression 4 having formed 60 at each end the aperture 5 as clearly shown in Fig. 2. At spaced intervals intermediate the ends of the tie and between the depressions 4 and the slots above referred to, which are in longitudinal alinement, are preferably provided with the loops 6 which are arranged to rest on the bedding material of the road and hold the tie in spaced relation thereto. The end loops 7 are preferably enlarged as clearly shown in Fig. 1 and are 70 so arranged as to eliminate any side slip of the tie and to lock the same firmly in place.

In the drawings in Fig. 5, the tie is illustrated as having an extension secured thereto and the two separate members are held together by means of the connecting element 8, which is bent to conform to the shape of the depression 4 and is provided with bolt receiving apertures through which the bolts 9 which secure the two members together are 80 adapted to extend. The rail clamps which are used in conjunction with this tie, and are each designated generally by the numeral 10, are preferably formed of a single sheet of material which is bent to form the rail 85 engaging element 11 having formed integral therewith the portion 12 which overlies the tie. This portion 12 is provided at its free end with the angularly extending tongue 13 and also has near its opposite end the 90 aperture 14 through which the T bolt 15 is adapted to extend. The head of the T bolt above mentioned, is adapted to seat in the notches 3 formed in the tie and thereby prevent the rail clamps from sliding longitudinally with relation to the tie.

It will be evident from the foregoing that in use, the tie is placed in position in the usual manner and the rails placed thereon, preferably between the first and second loop. 100 The rail clamps are each then placed in the desired position so that the tongue 13 formed thereon will project through the longitudinal slot formed in the tie. The T bolt is then put through the slot in the tie 105 and through the aperture in the clamp member in such a position that the head of the bolt will rest in one of the notches 3. Upon tightening the nut which cooperates with the bolt, it will be evident that the clamp 110 will firmly hold the rail in position and in view of the fact that the bolt is seated in

the notch, the same will be held from accidental displacement and spreading of the rails will be thereby eliminated.

While in the foregoing there has been shown and described the preferred embodiment of the invention, it is to be understood that such changes may be made in the combination and arrangement of parts as will fall within the spirit and scope of invention as claimed.

Having thus described my invention, I claim:

1. A device of the character described comprising a body portion, a plurality of centrally located, longitudinally extending slots formed in the body portion, depressions formed laterally of the body portion and in direct alinement with the slot, a plurality of loops formed in the under side of the body portion, the walls of said depressions being bent downwardly and being provided with notches, and rail clamps adapted to be secured to the tie and held from longitudinal movement by the notches.
2. In a device of the character described, a body portion formed of a single sheet of material, said body portion being provided with a plurality of longitudinally extending, centrally located slots, a plurality of depressed portions formed integral with the body portion, said depressed portions being in direct alinement with the longitudinal slots, a plurality of loops formed integral with the body portion, between the slots, said loops extending transversely across the tie, rail clamps adapted to coöperate with

the tie, the walls of the slots being provided with notches, and T bolts extending through the slots and the rail clamps, the heads of said T bolts engaging the notches to eliminate any danger of the rail coming out of alinement.

3. A device of the character described comprising a body portion formed of a single sheet of material, a plurality of transversely extending loops formed of the body portion and projecting downwardly therefrom, said body portion being provided with a plurality of longitudinal slots intermediate the loops, said longitudinal slots being centrally located with relation to the lateral extremities of the body portion, depressed portions formed integral with the tie at its lateral edges, said depressed portions being extended longitudinally of said tie, and being in direct alinement with the slots, the walls of the slots being bent downwardly, and having a plurality of notches formed therein, rail clamps, tongues formed on the rail clamps and adapted to enter the slots, and T bolts adapted to extend through the rail clamps to firmly hold the same in position on the tie, said T bolts being adapted to seat in the notches to prevent longitudinal movement of the rail clamps with relation to the tie.

In testimony whereof I affix my signature in presence of two witnesses.

WILLIAM V. POLICK.
